UNITED STATES PATENT OFFICE

OSCAR O. WOLFKILL, OF NEWTON HAMILTON, PENNSYLVANIA

SPLICE BAR

Application filed September 22, 1931. Serial No. 564,387.

This invention relates to railway rails and joints, and more particularly to the splice bars used in splicing the ends of rail sections.

The primary object of the invention is to provide a splice bar which will be exceptionally strong and durable, and one which will compensate for the movement between rail sections due to expansion and contraction, thereby eliminating any possibility of the splice bars buckling.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view illustrating splice bars constructed in accordance with the invention, a portion of one of the splice bars being broken away.

Figure 2 is a sectional view taken on line 2—2 of Figure 1.

Figure 3 is a sectional view taken on line 3—3 of Figure 1.

Referring to the drawings in detail, the reference character 5 designates the adjacent ends of rail sections which have been brought together in the construction of a track.

Since the splice bars forming the subject matter of this invention, are identical on both sides of the rail, the splice bar at one side of the rail will be described in detail.

The splice bar comprises sections 6 and 7 respectively, the sections being formed with bases 8 to accommodate the bases of the rail sections used in connection therewith.

As clearly shown by the drawings, the section 7 is formed with an extension 9 substantially square in cross section, the extension being fitted in a bore or opening formed longitudinally of the section 6, the bore or opening conforming in shape to the shape of the extension 9, so that a close fit between the extension 9 and opening or bore, will be insured at all times.

The splice bar sections are of widths to fit snugly between the base of the rail sections, and under surfaces of the ball or tread of the rail sections.

Elongated openings are formed in the extension 9, which elongated openings register with openings formed in the cooperating splice bar section and web of the rail with which the splice bar is used.

Thus it will be seen that due to this construction, movement of one section of the splice bar with respect to the other section will be permitted, when the rail sections expand or contract under heat and cold.

As shown by the drawings, the extension 9 of one splice bar at one side of the rail, is extended in one direction, while the extension 9 of the splice bar or section at the opposite side of the rail, is extended in the opposite direction, thereby providing a splice bar which will not only compensate for movement of the rail sections, but one which will be exceptionally strong and durable.

If desired, the splice bars may be arranged so that the extensions 9 extend in the same direction, without departing from the spirit of the invention.

The bolts which are indicated by the reference character 10 are of the usual and well known construction, and are provided with nuts 11 for tightening the bolts in position.

Cut out portions 12 are provided in the sections of the splice bar, for the reception of the usual spikes employed in securing the rails to the ties of the track.

The cut out portion in the section 6 of the splice bar is elongated to permit of movement of the splice bar sections upon expansion or contraction of the rail sections.

Having thus described the invention what is claimed is:

1. A splice bar comprising a pair of cooperating sections arranged end to end, a bar extending from one of the sections and extending into one end of the adjacent section, and bolts extending through the sections and rails with which the splice bar is used.

2. A splice bar comprising a pair of sections, one of said sections having a longitudi-

nal bore, a connecting bar extending from the adjacent section and fitted in the bore to slidably connect the sections, bolts extending through the bar and said connecting bar having elongated openings to receive the bolts.

3. A splice bar comprising a pair of sections arranged end to end, one of the sections having a bore extending longitudinally thereof from one end of the section, a connecting bar carried by the adjacent section and fitted in the bore to slidably connect the sections, and bolts for connecting the splice bar to the adjacent ends of the railway rails.

4. A splice bar comprising a pair of cooperating sections to be fitted over the sides of railway rails, one of said sections having a longitudinal bore square in cross section, an extension extending from the adjacent splice bar section, said extension being square in cross section, to fit snugly within the bore, said extension having elongated openings, the adjacent section of the splice bar having openings aligning with elongated openings to receive bolts, and said bolts extending through openings in railway rail sections.

5. A splice bar comprising a pair of sections arranged end to end, one of the sections having a bore extending longitudinally through the center thereof, an extension extending from one end of the adjacent section, and disposed within the bore, bolts extending through the extension and adjacent section to secure the sections of the splice bar together, and said extension having elongated openings to receive the bolts and allow movement of one section with respect to the other section.

In testimony that I claim the foregoing as my own, I have hereto affixed my signature.

40 OSCAR O. WOLFKILL.
